TWO CIRCUIT SNAP SWITCH

John O. Roeser, Chicago, Ill., assignor to Illinois Tool Works, Chicago, Ill., a corporation of Illinois

Application March 23, 1955, Serial No. 496,209

10 Claims. (Cl. 200—67)

This invention is concerned with the electrical switch art, and more particularly with a snap switch mechanism.

More specifically, this invention relates to a single pole, double throw switch of the type frequently called a two-circuit switch. It differs from ordinary single pole switches in that it is provided with four terminals, and a bridging contact member is adapted selectively to contact either of two pairs of terminals to complete a circuit. This type of mechanism is characterized by high electrical interrupting ability, long contact life, more adaptable circuitry and good vibration resistance with a small case.

Snap switches of the foregoing type currently find wide use in aircraft, and also find substantial use in industrial and business machine use. Prior switches of this type often have required critical tolerances and special heat treating. They often have relied upon flexible spring blades which must be made of critical materials in order to have relatively long service life. Different constructions have been necessary in order to impart different characteristics to the switches.

Accordingly, it is an object of this invention to provide a two-circuit snap switch comprised of parts which do not require critical tolerances and need not be heat treated in fixtures as in the prior art.

It is another object of this invention to provide a two-circuit snap switch utilizing a spring having a very long mechanical life.

Yet another object of this invention is to provide a two-circuit snap switch, the characteristics of which readily may be changed without reconstruction by the substitution of a different spring.

More specifically, it is an object of this invention to provide a two-circuit snap switch utilizing a dead centering coil spring as an actuating agent.

A further object of this invention is to provide a two-circuit snap switch which can be made entirely of non-critical materials.

A further object of this invention is to provide a two-circuit snap switch utilizing parts of simple design, thereby allowing the use of high temperature materials which often are hard to work in complicated shapes.

It is another object of this invention to provide a two-circuit snap switch having an improved guiding action for the actuating member, thereby providing an exceptionally good bearing for the actuating member and helping to hold the contacts in proper position.

It further is an object of this invention to provide a two-circuit snap switch wherein there is a positive wiping action of the contacts which serves to keep the contact surfaces clean and insures breaking loose of sticking or welded contacts.

It further is an object of this invention to provide a two-circuit snap switch having an improved contact carrying terminal.

Prior art terminals often have not been capable of satisfactory mounting in a plastic case so as to be secure against accidental removal through abuse, and so that they will not be loose or in any way rattle. It will be understood that undercuts are to be avoided in molds for plastics in general, and that therefore special con-

2

figurations of plastic cases generally cannot be relied upon to hold terminals properly in place.

Accordingly, it is an object of this invention to provide a terminal avoiding the foregoing difficulties.

More specifically, it is an object of this invention to provide a terminal cooperating with a plastic case wherein the terminal is provided with portions snapping into position in the plastic case for a secure mounting of the terminal.

10 Other and further objects and advantages of the present invention are to provide a two-pole four-circuit snap switch possessing the same advantages as the two-circuit single pole switch heretofore described, and to provide means in such a switch positively insuring simultaneous operation or snap movement of all of the moving contacts thereby to insure against improper switch operation.

Additional objects and advantages of the present invention will be apparent from the following description when taken in connection with the accompanying drawings wherein:

Fig. 1 is a perspective view of a switch constructed in accordance with the principles of my invention;

Fig. 2 is a longitudinal sectional view generally corresponding to a side view with the cover of the case removed;

Fig. 3 is a vertical cross sectional view taken along the line 3—3 in Fig. 2;

Fig. 4 is an exploded perspective view;

Fig. 5 is a horizontal sectional view taken substantially along the line 5—5 in Fig. 2;

Fig. 6 is a view similar to Fig. 2 showing the parts in a different position of operation;

Fig. 7 is a sectional view of the main portion of the case with a part of the case broken away;

Fig. 8 is a perspective view of the cover for the case;

Fig. 9 is a horizontal detail sectional view showing the mounting of the terminals as taken substantially along the line 9—9 of Fig. 6;

Fig. 10 is a vertical cross sectional view through the terminals taken substantially along the line 10—10 in Fig. 6;

Fig. 11 is a side view partially in section with the cover of the case removed generally similar to Fig. 2 and showing a two-pole, four-circuit switch;

Fig. 12 is an exploded perspective view of the switch shown in Fig. 11; and

Fig. 13 is a fragmentary sectional view similar to the central portion of Fig. 2 disclosing a modified structure wherein buttons project from opposite sides of the switch housing.

Referring now in greater particularity to the drawings, and first to Figs. 1—8, there will be seen a switch constructed in accordance with the principles of my invention and generally identified by the numeral 20. This switch comprises a housing having a main portion or body 22 and a cover 24. The switch case or housing is made of any suitable insulating material such as plastic Bakelite being a preferred example, and the cover 24 is held on the body 22 by any suitable means such as rivets (not shown) which are passed through a pair of aligned apertures 26 having enlarged counter-bores at their opposite ends. The aligned apertures 26 conveniently are diagonally disposed relative to one another on the case, and another pair of aligned apertures 28 completing a rectangular arrangement with the apertures 26 is provided for the receipt of mounting screws to hold the switch in any desired operational location and position.

The main portion or body 22 of the case is provided at its opposite ends with pairs of vertically spaced, horizontally disposed slots 30. These slots open at one end on the open side of the body and are closed off by the

cover 24. It will be observed with reference to Figs. 4 and 8 that the cover is provided with a peripheral shoulder 32 fitting about a complementary boss or projection 34 on the body 22 in order accurately to position the cover on the body, and also substantially to seal the case. Aligned with each of the slots 30 is a pair of circular holes or recesses 36 on a shelf 38 projecting from the back wall 40 of the body. Pairs of recesses or holes 42 (Fig. 8) are provided in raised shelves 44 and 46 on the front wall 48 of the cover. The slots 30 and the aligned pairs of recesses 36 and 42 cooperate to receive and support inserts 50 providing attachment terminals and also providing fixed contact supports.

Each of the inserts as best may be seen in Figs. 4, 9 and 10 comprises a substantially rectangular body portion having a terminal lug or ear 52 projecting outwardly and to one side. The lugs 52 are provided with apertures 54, and the upper and lower inserts are relatively reversed so that the lugs or ears project in relatively opposite directions to facilitate connection of wires thereto. Each insert 50 also comprises two pairs of oppositely extending parallel fingers 56. The inserts are stamped from a flat sheet of spring material such as brass, and the outer ends of each pair of fingers 56 approach one another more closely than do the inner ends. The fingers 56 are of a proper size to fit into the recesses 36 and 42, but the outer ends of the fingers are spaced slightly closer, for instance .005 inch, than are the corresponding recesses. Thus, the insert fingers must be snapped into the recesses and firmly grip the walls thereof to hold the inserts in place.

In addition to the foregoing parts each insert is provided with an aperture in the body portion thereof, and a contact element 58 of suitable conductive material, preferably silver, is riveted into each of these recesses in accordance with conventional contact mounting practice.

It will be apparent from the drawings and from the foregoing description that the contact elements 58 thus are mounted at opposite ends of the case in vertically spaced pairs, the elements being aligned with one another for selective engagement by a vertically movable double-faced contact.

The body 22 is provided at its center with a vertical guideway 60 opening towards the interior of the case, and a similar guideway 62 is provided in the cover confronting the guideway 60. An actuator 64 is arranged for vertical reciprocation in these guideways and comprises a sheet metal stamping of brass or the like of rather substantial thickness. The actuator is provided with a generally rectangular body portion having a reduced upstanding tongue 66. A plastic button 68 fits over this tongue and down against the shoulders 70 at the top of the body portion adjacent to tongue 66. The button is of rectangular cross section and is received mostly in a recess 72 in the top wall of the case body, and partly in a recess 74 in the cover, the two recesses cooperating to form a rectangular opening complementary to the button 68. The button is provided with an outwardly projecting circumferential flange 76 at its lowest edge to limit upward movement of the button and actuator.

The actuator is provided in the body thereof with a vertically elongated slot 78, and with a downwardly projecting spring locator 80, and a pair of downwardly projecting legs 82 spaced to either side of the spring locator. A coil spring 84 fits about the projection 80 and between the legs 82 and is positioned in a recess 86 in the case body 22. This spring normally urges the actuator 64 and the button 68 thereon upwardly to their upward limit of movement as shown in Fig. 2.

The actuator 64 is provided on its opposite faces with V-shaped grooves 88. These grooves are horizontally disposed across the center of the aperture 78 and are

positioned directly opposite to one another. The grooves are terminated inwardly of the edges of the actuator as may be seen at 90 in Fig. 4 and also in Fig. 3.

A contact blade 92 is pivotally mounted in each pair of grooves 88 on one side of the actuator. Each blade is U-shaped in configuration, comprising a pair of legs 94 and a bight 96. A double-faced contact button 98 is carried in each bight for engagement either above or below the contact blades 92. The inner ends of the blades, i. e. the ends 100 of the legs are sharpened and seat in the grooves 88 on opposite sides of the aperture 78. A coil spring 102 extends through the aperture 78 and is anchored at its opposite ends in small apertures 104 in the bight 96 immediately adjacent to the double-faced contact buttons 98. For the best possible switch action the apertures 104 anchoring the ends of the spring 102 are positioned as near as possible to the contact button 98. However, it is contemplated that tongues of greater or lesser length could extend parallel to and spaced from the legs 94 from the bights to provide spring anchors that are closer to one another and relatively remotely disposed to the contact buttons. However, it has been found that switching action in this case is inferior. The switch blades 92 best are made of a resilient spring material, and beryllium copper is a preferred example. The contact buttons 98 preferably are made of silver, similar to the contact elements 58, and the coil spring 102 is of conventional construction, commonly spring steel.

The spring 84 normally holds the actuator and actuator button in the raised position of Fig. 2 as previously has been noted. The tension spring 102 urges the arms or contact blades toward one another in a downward direction so that the contact buttons 98 engage the lower two contacts 58. When the button 68 is depressed against the force of the spring 84, the pivot of the contact blade 92 comprising the grooves 88 is lowered toward a dead center position relative to the spring 102 and the portions of the contact blade in which the spring is anchored. As soon as the pivot passes this dead center position the contact blades are snapped upwardly by the spring 102 to cause the contact buttons 98 to engage the upper pair of contact elements 58. This upper contact position is shown in Figs. 6 and 10. It will be apparent that the two contact buttons 98 move substantially in synchronism inasmuch as both buttons are snapped by the spring 102 as soon as the pivot passes dead center as heretofore has been noted. When the button 68 is released the spring 84 returns the button and actuator to the uppermost position, the pivot again passing through a dead center, and the spring 102 this time snapping the contact button 92 down into engagement with the lower contact element 58.

It will be apparent that the switch mechanism heretofore described is a spring-return switch. That is to say, the spring 84 normally maintains the actuator in the raised position of Fig. 2 so that a circuit is completed between the lower contact elements 58 by means of the contact buttons 98, the contact blades 92 and the actuator 64. The upper pair of contacts 58 is similarly connected only when the button 68 is held down. It will be apparent that the spring 84 could be omitted, and a tongue similar to the tongue 66 could be provided on the lower end of the actuator for cooperation with a second button 69, as illustrated in Fig. 13, projecting from the bottom of the switch. The switch thus would be manually operated in either direction and would remain in whichever direction it was actuated until a succeeding actuation in the opposite direction.

As has been noted heretofore the principles of my invention can be applied equally well to a two-pole, four circuit switch. Such a switch is shown in Figs. 11 and 12. It will be noted in these figures that the construction is generally similar to that heretofore shown and described with a duplication of certain other parts and

modification of others of the parts to conform with the duplication. To avoid prolixity of description, parts which are substantial duplicates of those heretofore shown and described are identified by the same reference numerals with the addition of suffix *a*. Certain of the parts which occur in duplicate in the modification of Figs. 11 and 12 are identified by the same numerals heretofore used with the addition of the suffix *b*. The body 22*a* and cover 24*a* of the case are of substantially the same length and thickness as in the original embodiment of the invention, but are somewhat higher. The case further is provided with a horizontal divider wall 104 extending from one end to the other of the body 22*a* and from side to side thereof. The horizontal divider wall 104 is provided with a transverse slot or guideway 106 for accommodating the actuator 64*a*. Inserts 50*a* and 50*b* are provided in duplicate pairs and are received in duplicate slots 30*a* and 30*b* in the ends of the case body. The horizontal divider wall 104 is provided with oppositely disposed recesses 108 at its opposite ends for accommodating the butts of the lower contacts 58*a* and the upper contacts 58*b*.

The actuator 64*a* is provided with two pairs of V-shaped grooves or recesses 88*a* and 88*b* on opposite sides of an insulating bar 109 in the actuator receiving the knife edges of two pairs of contact blades 92*a* and 92*b*. The aperture 78*a* in the actuator is sufficiently elongated in height to accommodate a pair of tension springs 102*a* and 102*b* stretched between the ends of each pair of contact blades. It will be observed in Fig. 12 that each of the contact blades is provided with a central tongue spaced between and extending parallel to and in the same direction as the legs or arms 94*a* and 94*b*. These tongues are numbered 110 for each of the contact blades and provide spring anchors spaced inwardly a short distance from the contact buttons 98*a* and 98*b*.

The purpose of the tongues in this embodiment of the invention as opposed to the previous embodiment wherein the tongues were omitted is to provide an anchor for a shift rod 112. This shift rod is provided with circumferential grooves 114 near its opposite ends and these grooves fit between the corresponding tongues 110 and adjacent arms or legs 94*a* and 94*b* to insure synchronous movement of the corresponding contact blades 92*a* and 92*b*. The shift rod 112 is made of any suitable insulating material such as plastic and fits through a recess 116 in the horizontal divider wall 104.

Operation of the switch shown in Figs. 11 and 12 is generally similar to that previously disclosed. Depression of the operating button 68*a*, and hence of the actuator 64*a*, against the force of the spring 84*a* causes the contact blades 92*a* and 92*b* and the springs 102*a* and 102*b* to move toward dead center positions. Generally speaking, one of the pairs of switch blades will trip first while the other is very near its trip point, say within .005 inch. The contact blade that first trips will fly through the air unrestrained, by virtue of a slight lost motion connection between the blades and the shift rod by virtue of forming the grooves in the shift rod slightly wider than the thickness of the contact blade, the lost motion generally being on the order of about .008 inch, until it hits solidly against the shift rod. The momentum gained by the moving contact blade hammers the other blade over center. This over-centering of the second blade, or pair of blades, is accomplished very easily since the second pair of blades is poised in substantially dead center position. It will be apparent that the shift rod is held against transverse motion by the tongues 110 and adjacent arms or legs 94*a* and 94*b*, and is held against longitudinal motion by fitting in the recess 116 in the horizontal dividing wall 104.

The switch again has been illustrated as a spring return type, but it will be understood that it readily could be made as a two-position manually actuated switch by eliminating the spring 84*a* and providing a second push

button in the bottom of the case fitting on a tongue at the bottom of the actuator.

It will be understood that each contact blade could comprise a single central leg with two springs on the opposite sides thereof. Furthermore, the grooves or notches 88, rather than being positioned directly opposite one another, could be offset to provide a predetermined sequential action.

It now will be apparent from the foregoing description that the parts of this switch do not require critical tolerances, and that the parts need not be heat treated in special fixtures as usually is necessary. The switch can be constructed of non-critical materials, and high temperature materials readily can be utilized since there are no complicated shapes to be formed. The helical tension springs utilized for the snap action have a very long mechanical life, and the characteristics of the switch may be changed easily without any changes in tooling simply by using different coil springs. The actuator is supported substantially over its entire length so that the operating button has an exceptionally good bearing. This helps to maintain good alignment so that the contacts are accurately positioned. Furthermore, it will be appreciated that there is a desirable and positive wiping action of the contacts which tends to keep the contacts clean, and facilitates breaking loose of sticking or welded contacts.

The particular structural embodiments of the invention heretofore shown and described will be understood as being for illustrative purposes only. Various changes in structure will no doubt occur to those skilled in the art, and are to be understood as forming a part of my invention insofar as they fall within the spirit and scope of the appended claims.

The invention is claimed as follows:

1. A snap switch mechanism comprising an insulating support, an actuator mounted in said support for slidable movement from a normal position to a second position, means for slidably moving said actuator relative to said support, means to return said actuator from said second position to its normal position, a pair of discrete switch blades pivoted on opposed sides of said actuator and extending generally transversely of said actuator, said switch blades being generally flat and each consisting of a pair of spaced arms interconnected at one end thereof by a bight portion, said actuator having generally opposed means to provide a pivot for said blades and located on the actuator in a mean position between extremes of sliding movement of said actuator, a helical spring stretched between said switch blades and attached to means integral with each bight portion, electrical contact means carried by each of said switch blades substantially at the outer ends thereof, and a pair of spaced abutment means respectively on opposite sides of each switch blade in a position substantially adjacent the outer ends of each of said blades, said abutment means being carried by said support and disposed substantially about the mean position of said pivot, a corresponding one of each pair of abutment means comprising an electrical contact aligned with the corresponding contact means carried by the switch blade, said switch blades synchronously snapping from a normal position engaging one of each pair of said abutment means to a second position engaging the other of each pair upon slidable movement of said actuator to carry the pivots of said blades on the actuator past a dead center position relative to said blades and spring means, said blades in one of said positions effecting with said contact means carried thereon a bridging electric circuit between said electrical contacts mounted on said abutment means.
2. A snap switch mechanism comprising an elongated insulated case having a channel shaped cavity located transversely of its elongated axis, and a second cavity extending longitudinally of said case and emanating outwardly in both directions from said channel shaped cavity,

and an actuator transversely mounted in said channel shaped cavity for slideable movement from a normal position to a second position, said actuator comprising an elongated member of conductive material having an elongated aperture therethrough along its longitudinal axis and within the margins thereof, a dielectric button attached to one end of said actuator and movably projecting through one side of said case, whereby depression of said button will move said actuator from a normal position to a second position, means to return said actuator from said second position to its normal position, a pair of discrete switch blades pivoted on said actuator and extending generally oppositely to one another and transversely of said actuator into the longitudinal cavity of said case, said switch blades being generally flat and each consisting of a pair of spaced arms interconnected at one end thereof by a bight portion, said actuator being provided with a pair of notches on opposite sides thereof in generally opposed position, said notches being positioned and extending outwardly from, and on opposed sides of, said elongated aperture and transverse to the longitudinal axis of said actuator, the free ends of the spaced arms on each blade being positioned within adjacent notches, said notches providing a pivot for the blades on said actuator having a mean position between extremes of sliding movement of said actuator, a single metallic coil spring stretched through the elongated aperture in the actuator between said switch blades and attached to each blade on its bight portion, electrical contact means carried by each of said switch blades substantially at the outer ends thereof and extending on opposite sides of each blade, a pair of spaced abutment means located at each end of the longitudinal cavity in the case and substantially symmetrically disposed in planes about the mean position of said pivot, a corresponding one of each pair of abutment means comprising an electrical contact aligned with the corresponding contact means on the adjacent switch blades, said switch blades synchronously snapping from a position engaging the other of each pair of abutment means to a position 40 engaging the other of each pair of abutment means upon slideable movement of said actuator, whereby the pivot point of said blades on the actuator is carried past a dead center position relative to said blades and spring means, said blades in one of said positions effecting with said contact means carried thereby a bridging electric circuit between the electrical contacts comprising the corresponding abutment means.

3. A snap switch mechanism as set forth in claim 1 wherein the case is provided in its opposite ends with a pair of spaced apart parallel slots at least in said body, substantially flat metallic inserts received in said slots and extending outside of said case and inside of said case, said inserts providing said abutment means and also providing electrical terminals, said inserts having oppositely extending pairs of resilient fingers coplanar with said body, each pair of fingers extending in the same direction and having confronting lateral edges, and an abutment inside said case cooperable with each pair of resilient fingers and resiliently gripped between said confronting lateral edges of such fingers for holding said inserts in place.

4. A snap switch mechanism as set forth in claim 3 wherein the abutments receiving the fingers comprise sections of material between spaced recesses in the case body and in the case cover.

5. A snap switch mechanism as set forth in claim 2 wherein the means to return said actuator from said second position to its normal position includes a second dielectric button attached to the end of said actuator opposite from said first mentioned button and movably projecting through the opposite side of said case from said first mentioned button.

6. A snap switch mechanism as set forth in claim 2 wherein said actuator is further provided at the end 75

opposite to said dielectric button, with a recess opening outwardly from said end and having a convex portion at the bottom thereof which is spaced from and partially encircles one end of said elongated aperture, spring means positioned within said first mentioned channel shaped cavity, biased between said case and said actuator, said convex portion of the actuator cooperating to center and retain said spring means whereby said spring means serves to return said actuator from said second position to its normal position upon release of pressure from said button.

7. A snap switch mechanism comprising an insulating support, an actuator mounted in said support for slideable movement, means for slidably moving said actuator, a plurality of pairs of switch arms pivoted on said actuator and extending generally oppositely of one another and transversely of said actuator, coil spring means stretched between each pair of switch arms, electrical contact means carried by each switch arm substantially at the outer end thereof, a pair of spaced abutment means on opposite sides of each switch arm substantially at the outer end thereof, said abutment means being carried by said support, a corresponding one of each pair of abutment means comprising an electrical contact aligned with the corresponding contact means, insulating means linking a corresponding one of each pair of switch arms to insure substantially simultaneous movement thereof, said switch arm synchronously snapping from a position engaging one of each pair of abutment means to a position engaging the other of each pair upon slideable movement of said actuator to carry the pivots of each pair of arms on said actuator past a dead center position relative to said pair of arms and the corresponding spring means, said arms in one of said positions effecting with said contact means a bridging electric circuit between said electrical contacts.

8. A snap switch mechanism as set forth in claim 7 wherein the switch arms and the linking means have a lost motion connection.

9. A snap switch mechanism as set forth in claim 7 wherein the linking means comprises an elongated insulating member having a plurality of grooves therein receiving the linked switch arms.

10. A snap switch mechanism as set forth in claim 9 wherein each switch arm is substantially U-shaped having a bight and a pair of arms extending therefrom, said bight being positioned outwardly from the actuator, and a tongue extending from said bight substantially parallel to said arms and in the same direction, said tongue and one of the arms fitting in the groove of said insulating member.
